UNITED STATES PATENT OFFICE.

THOMAS H. BENTON, OF PORTSMOUTH, VIRGINIA.

MATTRESS.

1,088,959.

Specification of Letters Patent.

Patented Mar. 3, 1914.

Application filed May 18, 1911. Serial No. 627,991.

To all whom it may concern:

Be it known that I, THOMAS H. BENTON, a citizen of the United States, residing at Portsmouth, in the county of Norfolk and State of Virginia, have invented certain new and useful Improvements in Mattresses; and I do hereby declare the following to be a full, clear, and exact description of the invention, such as will enable others skilled in the art to which it appertains to make and use the same.

This invention relates to mattresses and the object is to provide means for protecting the corners thereof in order to prevent the fabric from becoming damaged and the mattress from being jammed in such manner as to destroy the shape thereof.

In the accompanying drawings forming a part of this application:—Figure 1 is a perspective view of a portion of a mattress having a protecting device on the edges thereof. Fig. 2 is a perspective view of the protecting member as seen from the inner side. Fig. 3 is a perspective view showing several mattresses placed together and having their outer edges protected. Fig. 4 is a perspective view of another form of the device. Fig. 5 is a detail view in perspective.

80 In carrying out my invention I make use of a mattress 10 constructed in the ordinary manner and apply to the edges thereof and especially to the corners protecting means comprising members 15 and 20 which have 85 slideable or telescopic connection with each other in order that similar devices may fit mattresses of various thicknesses.

The device 15 consists of a flat portion 16 having connected with two of the side edges thereof members 17 and 18 which are in turn connected at the corner 19. Tying and bracing devices 21, 22, 23 and 24 are provided and are arranged in the manner shown in Fig. 1. The lower member 20 is 45 similarly formed.

In Fig. 2 is illustrated the manner of connecting the various portions of the side walls together in order to form a rigid construction with a given amount of material. 50 The side wall 17 consists of three main layers 25, 26 and 27, the supplemental layer 26' being continuous with the layer 28 of the portion 15. Side wall 18 includes two layers 29 and 30 and the inner layer 30 ex- 55 tends beneath the inner layer 28 of member 15.

Supplemental layer 26' of side member 17 has formed thereon a tongue 32 which passes through a slot in layer 25 and the middle layer of member 15 has a similar tongue 33 connected therewith passing through a slot 34 in layer 28. The tongue is formed with laterally extending ears and constitutes a locking device. That portion of the middle layer of member 15 which carries the tongue 33 may be cut separately from the main layer, the meeting edges of the sections being tapered at a point slightly to the left of the extreme lower corner of Fig. 2.

The inner corner bracing member 40 is secured to the inner layers of the side walls and a similar device 41 connects members 15 and 17.

In Fig. 3 I have shown devices of this character as I intend to use them for protecting the outer mattresses when several are shipped together in the form of a bale. The construction may be substantially the same as that above described and the illustration is intended to show one way in which the device may be advantageously employed.

In Fig. 4 a further form of the device is illustrated, this construction being box-like in form and obviously made to conform to the thickness of the mattress for which it is intended. The side walls of this construction are indicated by the numerals 45 and 46, these walls being continuous with the end walls. End wall 47 is continuous with side member 46 and end wall 48 is continuous with side wall 45. These side walls also overlap at the lower portion as the box appears in Fig. 4. Reinforcing strips 49 and 50 protect certain of the corners and inner reinforcing strips 52 and 53 are located in the corresponding inner corners. Additional reinforcing devices 54, 55 and 56 may be provided on the outside and strips 57 and 58 on the inside, in the positions shown.

A device of this character is especially useful in protecting the corners of a mattress used in a sleeping car, in a hospital or in any place in which changes are constantly being made. It is also employed to advantage in shipping mattresses in order to protect the edges thereof.

What I claim is:—

In a device of the class described, a mattress and a reinforcing device therefor com-

prising a three-sided box-like member arranged to cover a plurality of sides and corners of the mattress, and a second member corresponding therewith, the said box members each overlapping the other along certain sides and having one side free, and said members being formed of a plurality of layers, means for bracing the corners of the inner layers, means for bracing the corners 10 of the outer layers, and reinforcing means for connecting the inner layer with one of

the intermediate layers near the edge and at a point remote from the corner of each box member, the means last mentioned being formed integrally with said intermediate 15 layer.

In testimony whereof I affix my signature in presence of two witnesses.

THOMAS H. BENTON.
